UNITED STATES PATENT OFFICE.

EZRA A. ARMSTRONG, OF SAMARIA, MICHIGAN, ASSIGNOR OF ONE-HALF TO
A. W. LEFLER, OF TOLEDO, OHIO.

DESIGN FOR A PAPER-BOX BLANK.

SPECIFICATION forming part of Design No. 29,251, dated August 16, 1898.

Application filed January 14, 1898. Serial No. 666,710. Term of patent 14 years.

To all whom it may concern:

Be it known that I, EZRA A. ARMSTRONG, a citizen of the United States, residing at Samaria, in the county of Monroe and State of Michigan, have invented and produced a new and original Design for a Paper-Box Blank; and I do hereby declare the following to be a full, clear, and exact description of the same, reference being had to the accompanying drawing, forming a part thereof.

This invention relates to a design for a paper-box blank, as illustrated in the accompanying drawing, which shows the blank in accordance with the design.

The blank A includes many contours and arrangements already well known, such as longitudinal and transverse straight score-lines b and d, arranged equal distances apart and forming a square bottom portion E. The lines b are continued outwardly from their points of intersection with the lines d by divergent score-lines e, forming opposite sides D of the box when the parts are folded, and the said lines b also form straight bases for divergent flaps B, having outer regularly curved edges a' and opposite straight sides a. These flaps have slits therein at the center near the edges a', having outer straight walls c and inner curved walls c'. The flaps B, with the sides D and bottom E, complete the box-body, and all the features thus far set forth are of well-known configuration.

The essential feature of the design resides in the locking-flaps C, having tongues F. The several locking-flaps are located at the four corners of the blank, and each is the exact

duplicate in shape of the others. These locking-flaps begin at the score-lines e and have rear curved unbroken edges h adjacent the straight edges a of the flaps B and form with 40 said latter edges the opposite boundaries of openings h'. This reduces the ends g', and the latter are straight and in part taken up by and absorbed in the outer portions of the tongues F. The tongues F are rectangular 45 in shape and are located at the extreme outer corners of the said locking-flaps. The said tongues all have inner straight score-lines g and the inner straight ends of the same are each clear and forms the longer side of a substantially rectangular slot f, having the outer 50 termination of its opposite shorter wall meeting an oblique edge i, merging into the outer straight edge of the adjacent side D. The locking-tongues are on the opposite ends and 55 form a part of the sides D, and the outward extent of the edges g' is less than the greatest width of the sides D from the score-lines d, and consequently the tongues F, slots f, and oblique edges i are recessed relatively to the 60 plane of the outer edges of said sides D.

Having thus described the invention, what is claimed as new is—

The design for a paper-box blank, as herein shown and described. 65

In testimony whereof I affix my signature in presence of two witnesses.

EZRA A. ARMSTRONG.
